Primary Examiner — Ruth McInroy(74) *Attorney, Agent, or Firm* — Fitch, Even, Tabin & Flannery, LLP**(57) CLAIM**

I claim the ornamental design for an auxiliary cyclonic dust collector, as shown and described.

DESCRIPTIONFIG. 1 is a perspective view of an auxiliary cyclonic dust collector in accordance with my new design; and,
FIG. 2 is a top view of the auxiliary cyclonic dust collector of FIG. 1.

The details shown in broken lines form no part of the claimed design.
